FIG 1

FIG 2

FIG 3

FIG. 4

FIG. 1 is a front, perspective view of a bathroom module showing my new design.

FIG. 2 is a rear perspective view of said bathroom module.

FIG. 3 is a sectional view taken on the line 3—3 of FIG. 2.

FIG. 4 is a perspective view, the front and a side of my module being broken away, showing the interior thereof.

The broken line representation of a water closet in FIGS. 3 and 4 is for purposes of illustration only.

I claim:

The ornamental design for a bathroom module or similar article, substantially as shown and described.
